UNITED STATES PATENT OFFICE.

MARTIN L. NELSON, OF CHICAGO, ILLINOIS, ASSIGNOR TO AUTOMATIC ELECTRIC COMPANY, OF CHICAGO, ILLINOIS, A CORPORATION OF ILLINOIS.

AUTOMATIC TELEPHONE SYSTEM.

Application filed June 30, 1919, Serial No. 307,561. Renewed November 2, 1922. Serial No. 598,647.

To all whom it may concern:

Be it known that I, MARTIN L. NELSON, a citizen of the United States of America, and a resident of Chicago, in the county of Cook and State of Illinois, have invented certain new and useful Improvements in Automatic Telephone Systems, of which the following is a specification.

My invention relates in general to an improvement in automatic telephone systems and more specifically to improved devices and circuits for calling and signalling any of the parties on a rural party line by means of codes.

Among the objects of my invention are to provide improved code calling mechanism for automatically signalling a party on a multiparty line whether the called party is on the calling line or another line and to provide other features and details of improvement which tend to provide a highly satisfactory code calling system for use especially in rural communities where the number of parties per line is often far above the average of the city party line.

In order to give such service a connector must be provided for calling to straight lines in case there are such lines, also to trunk lines leading to another exchange, and must also call to 8 or 12 party lines. Means must also be provided for enabling a subscriber on an 8 or 12 party line to call any other subscriber on the same line.

In the drawings I have shown in Fig. 1 a connector switch H which is assumed to be accessible through line switches and selector switches (not shown) of the standard two wire Strowger type to all the lines in the exchange and which has access through its wipers to trunk lines leading to another or a main exchange. Associated with the connector H is a code selecting switch B and a code switch C.

In Fig. 2 I have shown a ring back switch D which is accessible to the same selector switches as the connector H and which is used whenever a subscriber desires to signal another party on his own line. The ring back switch D is in the nature of a code selector and has access to a code switch C' similar to that shown at C (Fig. 1).

Common to the connector switches H and the ring back switches D is a code interrupting device I whose function will be explained.

In order to describe the operation of the system I will first describe the method of operation when a subscriber seizes the switch H and operates the switch to seize a rural or multi party line and signals a desired subscriber thereon by means of a code. In this case when the connector H is seized a circuit is completed for the line relay 2 of connector H in series with the calling telephone line or repeater as the case may be. Relay 2 energizes and closes a circuit at springs 3 and 4' for slow release relay 5, which in turn energizes to supply ground to the release trunk through springs 6 and to prepare a circuit for the vertical magnet 7 and slow relay 8 through springs 9 and 10. As soon as the calling device is operated to send a digit, relay 2 operates in accordance therewith to close the circuit of vertical magnet 7 and relay 8 a corresponding number of times. Magnet 7 operates to step the wipers 11, 12 and 13 to a desired level of the bank in which the called line is located. Relay 8 remains energized to hold a new circuit closed for itself and magnet 7 after the switch steps off normal, said circuit extending from ground through springs 3 and 4, springs 9 and 10, springs 14 and 15, springs 16 and 17 and relay 8 and magnet 7 to battery. As soon as the impulses for this digit cease, relay 8 falls back to close or prepare a circuit through springs 16 and 18 for slow relay 19 and rotary magnet 20 in multiple, so that as relay 2 responds to the next digit, relay 19 energizes and remains energized, while magnet 20 operates to step the wipers 11, 12 and 13 to the contacts of the called line.

Relay 19 remains energized for a short interval after the called line is found so that, if the called line is busy and ground is present on its test contact, then busy relay 21 will energize to lock the switch on busy and give the calling subscriber a busy signal.

If the called line is idle, however, then when relay 19 falls back, a circuit is completed from ground through springs 6 of relay 5, springs 22 and 23, lower winding of relay 24, springs 25 and 26, wiper 12, and through the bridge cut off relay of the called line switch to battery. Relay 24 energizes and locks itself to ground through springs 27, opens the circuit of relay 21 at springs 28, opens the circuit of magnet 20 at springs 29 and 30, prepares a circuit for certain re-

lays of code selector B at springs 29 and 31, puts ground on the private wiper 12 direct through springs 33, grounds lead 34 to switch B at said springs 33 and cuts the line 5 circuit through to wipers 11 and 13. Now the calling subscriber will operate his calling device in accordance with the last digits of the called number which is for the application of the proper code to the called line. As relay 2 operates in accordance with the first of these digits, a circuit is intermittently closed from ground through springs 3 and 4, springs 9 and 10, springs 14 and 15, springs 16 and 18, springs 37, 10 springs 29 and 31, conductor 45, springs 38 and 39, relay 35, and vertical magnet 36 to battery. This switch B is of the two motion type of switch in which the wipers are first raised to some level and then rotated to 15 a desired set of contacts upon which a desired code may be found. The magnet 36 operates to step the wipers 40 and 41 to the level of the bank in which the desired code is located. Relay 35 energizes on the first 20 impulse and remains energized, due to its slow action, until after the last vertical impulse comes in. This relay 35 holds a new circuit closed for itself and for magnet 36 extending from conductor 45, through 25 springs 38 and 42, springs 43 and 44, and through relay 35 and magnet 36 to battery as soon as the switch takes its first step to open springs 38 and 39 and close the springs 38 and 42. After the last vertical impulse 30 comes in relay 35 falls back to prepare a new impulsive circuit from the line relay 2 of the connector H, said circuit extending from the conductor 45, springs 38 and 42, springs 43 and 46, springs 47, relay 48, and rotary magnet 49 to battery. During the impulses corresponding to the last code digit relay 48 35 stays in energized position to hold a short circuit about the springs 47 at springs 50, closes a circuit for relay 51 at springs 52, and opens one point in the circuit of the 40 rotary magnet 54, of the code interrupter switch C at springs 53. Relay 51 energizes and locks energized from ground through springs 32 of relay 24 of the connector 45 through springs 55 and 56, and springs 57 to relay 51 and battery. Relay 51 also opens the springs 47, closes the springs 58 in the circuit of magnet 54, supplies an additional ground to conductor 34 of connector H, and 50 closes a circuit from ground through springs 59, over conductor 60, to the interrupter mechanism I. The interrupter I is simply a series of relays which interrupt each others circuits to cause an intermittent ground to be applied to a series of conductors such as 61 and 62 one of which conductors may lead to a single switch or to a group of switches. Any standard type of machine interrupter may be used in place of the relays I. As 55 soon as relay 48 falls back after the rotary 60 impulses have ceased the wipers 40 and 41 stand in connection with the third, 6th, 15th and 18th contacts in the bank of contacts accessible to a wiper 63, which is rotated over its contacts by a magnet 54. Magnet 54 70 starts its operation as soon as the springs 53 of relay 48 close when that relay falls back, the circuit extending from ground through springs of interrupter I, conductor 61, springs 53, springs 58, and magnet 54 75 to battery. The wipers 63 and 64 move together on a common shaft. Assume the code number called to be 22, that is, the wipers of the switch B have been raised to the second level and rotated to the second contact and it is desired to ring the bells on the connected with party line, 2 rings, pause and 2 rings which is the code of the called party. As soon as the wipers 63 and 64 reach the 80 first contact a circuit is completed from ground through wiper 64, wiper 63, contact #1, lead 65, relay 66 and resistance 67 to battery. Relay 66 locks energized over conductor 68 to ground at switch H, and closes the springs 69 in the circuit of ringer relay 90 70. Relay 70 energizes to connect generator current to the called line and to the various bells thereon as follows: Springs 71 and 72, springs 73 and 74, springs 75, wiper 13, to and through the bells of the called party 95 line, and back through wiper 11, springs 76 and 77, and upper winding of ring cut off relay 78 to battery. Relay 78 is the usual type of ring cut off relay and does not energize with ringing current. The ground 100 which energizes relay 70 it will be seen is the same that operates the magnet 54 of the switch C, and therefore relay 70 energizes once for each step of the wipers 63 and 64. 105 The first time relay 70 energizes therefore is by the same ground impulse which steps the wiper 63 to its second contact. As the second contact has no connection with wipers 40 and 41 relay 66 remains locked up and another ground impulse operates the wiper 110 63 to its third contact and also energizes relay 70 to ring a second time. As the wiper 63 reaches the third contact, a circuit is closed from ground through said wiper, contact #3, conductor 79, wiper 40, and relay 80 115 to battery. Relay 80 operates to open the springs 81 in the circuit of relay 70 so that the next impulse to magnet 54 does not operate said relay and therefore leaves a pause 120 in the ringing of the bells. As wiper 63 in response to this impulse moves to contact #4 the circuit of relay 80 is again opened and springs 81 close to allow relay 70 to be energized twice again in succession as wiper 63 125 moves first to contact #5 and then to contact #6. As wiper 63 reaches contact #6 a circuit is completed from ground through said wiper, contact #6, conductor 82, wiper 41, and resistance 67 to battery, thus shorting out the relay 66 which has been locked 130

energized. Relay 66 therefore falls back to open the springs 69 to prevent energization of relay 70 again until the wiper 63 reaches the contact #13, which is multiplied with 5 contact #1 so that at that time relay 66 will again be energized over conductor 65 to start the same cycle of operations as the wiper moves over contacts 13 to 18 inclusive.

This operation of the switches B and C 10 continues until the called subscriber answers or until the calling subscriber hangs up to release if the called man does not answer.

As soon as the called subscriber answers a 15 circuit is completed for the upper winding of the ring cut off relay 78 through the closed circuit of the called line, and said relay energizes and locks energized through its lower winding to ground at springs of release relay 5. Relay 78 also opens the springs which 20 disconnect the ringing circuit from the called line, opens the springs 55 and 56 in the holding circuit of relays 51 and 66 of the switch B, and cuts the called line through to the calling line at the front contacts of springs 25 76 and 74. Relay 51 of the switch B, which has been held energized from the ground through springs 55 and 56, now falls back as soon as switch C reaches one of its normal positions and opens the starting circuit of 30 the interrupter I and also the springs 58 in the impulsive circuit from interrupter I so that magnet 54 of the code switch C now stops. Conversation may now proceed between the calling and called subscribers over 35 the heavy conductors shown through the switch H. The back bridge relay 83 of the switch H having energized as soon as the relay 78 cuts the line through, reverses the connections of the line relay 2 with regard to the 40 talking circuit to reverse battery for metering or supervisory purposes.

When conversation is completed and the calling subscriber hangs up his receiver to release the connection, the line relay 2 of 45 switch H falls back and relay 83 also falls back when the called subscriber hangs up. Relays 2 and 83 jointly close circuits for the release relays 81 of switch H and 84 of the code switch B, thereby releasing said 50 switches to normal.

With regard to the code switch C (Fig. 1) it is to be understood that although I have shown only two sets of the banks in the code selector B wired to certain codes in the bank 55 of the switch C yet there may be a large number of codes taken from this same switch C by means of the other contacts being wired to similar adjacent contacts in the various levels of switch B. For instance, the #11 set of bank contacts or the first set of contacts of the first level of switch B, is connected to contacts #2 and 4 of switch C and rings one-pause-one. Other contacts may be wired in a similar manner to represent other 60 codes such as 1-4, 2-5, etc., the number of 65

codes being equal to the largest number of stations on a party line.

The switch D (Figure 2) is a switch that is set apart for ring back calls only and is accessible through some level of the selector 70 switches of the system which is set apart for calls from one station on a party line to another station on the same line. When a calling subscriber seizes a selector switch and operates it to its special level by means of his 75 calling device, connection will therefore be extended to an idle one of a group of switches such as D.

As soon as a selector seizes a switch such as D, a circuit is completed for the line 80 relay 100 thereof, which relay energizes to close the circuit of relay 101 at springs 102 and 103. Relay 101 energizes to connect ground through springs 105 and 106, and through springs 107 and 108 to the holding 85 trunk 109 of the selector, prepares a circuit at springs 110 and 111 for relay 112 and magnet 113 and opens a point at springs 108 and 114 in another circuit. As soon as the calling subscriber operates his calling 90 device for the code selecting or last two digits of the called number, relay 100 operates in response thereto to control relay 112 and magnet 113. Relay 112 remains energized during the impulses of the first digit 95 to hold a new energizing circuit for itself and magnet 113 closed after the off normal springs are operated by the first vertical step of the switch, and magnet 113 operates to step the wipers 115 and 116 to the desired 100 level of its bank. As soon as relay 112 falls back after the first digit a circuit is prepared for the slow relay 117 and rotary magnet 118 through springs 119 and 120. When relay 100 operates for the impulses 105 of the next digit, therefore, relay 117 and magnet 118 are operated. Magnet 118 operates to step the wipers 115 and 116 to the desired contacts to which the code of the wanted subscriber is connected, and relay 110 117 energizes to close a circuit through springs 121 and relay 122 to battery. Relay 122 energizes and is locked energized through springs 123 and off normal springs 124 to ground. Relay 117 also holds springs 115 125 open in the circuit of relay 126. It will be understood that the code interrupter switch C' is exactly like the switch C (Fig. 1) and is wired in the same manner to the banks of the switch D, and I have shown 120 the same codes wired up in this switch C' as in the switch C.

After relay 117 falls back the springs 125 are closed to prepare the circuit of relay 126 which is now held open at springs 102 and 104 of the line relay 100. In this type of a ringback call the calling subscriber hangs up his receiver as soon as he has operated his dial to send in all the digits, and thereby opens the circuit of line relay 100 of the 130

- switch D. Relay 100 falls back and completes the circuit of relay 126 through springs 102 and 104, springs 110 and 111 and springs 125.
- 5 Relay 126 energizes to close springs 127 which completes a new energizing or locking circuit for release relay 101 through springs 135 of relay 136, springs 108 and 107, and springs 106 and 105 to ground, preventing the release of the selector switch. Relay 126 also disconnects the line relay 100 from the calling line at springs 129 and 130 and springs 131 and 132, and completes a ringing circuit for the bells of the calling station through the springs 137 of relay 136 and to spring 138 of relay 139 which spring is later to be switched from ground to ringing current. The closure of springs 128 by relay 126 closes an energizing circuit for the relay 140.
- 10 Relay 140 upon energizing closes a ground circuit to start the interrupter relays I and also completes the circuit from conductor 62 through springs 141 to the rotary magnet 54' of the switch C' to start the step by step operation of the switch C' over its bank.
- 15 As the wiper 63' of switch C' reaches its first contact, a circuit is completed from ground through said wipers, conductor 142, relay 143 and resistance 144 to battery. Relay 143 energizes to close the springs 145 in the circuit of ringing relay 139. Now as the next ground impulse comes over conductor 62 to step the wipers 63' and 64' to their second contact, the ground also passes through springs 146 and springs 145 to relay 139.
- 20 Relay 139 energizes momentarily to connect generator current through spring 138 and its front contact to the calling line and back over the other side of the line through springs 131 and 133 and through the lower winding of ring cut off relay 136 to battery. The next impulse of ground moves wipers 63' and 64' to the third contact and operates relay 139 to ring once more.
- 25 When the wiper 63' reaches contact #3 however, a circuit is completed for the relay 147 over wiper 115 and its contact and relay 147 opens springs 146 to prevent the next ground impulse, which moves wipers 63' and 64' to their fourth contacts, from operating relay 139, thus causing a pause in the ringing. Relay 147 falls back as soon as wiper 63' leaves the third contact
- 30 and the ring proceeds for two more steps until the wiper 63' reaches the #6 contact at which time a circuit is closed from ground through wiper 63', contact #6, wiper 116, and resistance 144 to battery,
- 35 thus short circuiting the relay 143 and causing it to fall back and open the springs 145 in the circuit of relay 139. Relay 143 will remain back until the switch C' reaches its 13th contact, at which time the ringing will again proceed in the same manner.

As soon as the called subscriber removes his receiver in response to the ringing of his bell in accordance with his particular code, a circuit is completed for the ring cut off relay 136 in series with the called line 70 circuit and relay 136 therefore energizes to cut off the ringing circuit at springs 137, locks itself to ground through its upper winding, removes ground from the release trunk by opening springs 105 and 106, opens 75 the springs 135 in the holding circuit of relay 101 and closes a circuit at springs 105 and 148 for the release magnet 149 through the off normal springs. Relay 126 is held energized until the switch D releases and 80 therefore prevents the line relay 100 from again energizing, and as ground is removed from the release trunk, the selector and subscribers individual line switch will therefore release also. 85 However, since the called man now has his receiver off the line switch will immediately re-operate and extend the line to the same or another selector, after which the line relay of the selector will feed battery current for talking to the calling line and the calling and called men may converse over the local circuit of their own line, the calling man having again removed his receiver when he noticed the stopping of the 90 bells of his own station occasioned by the response of the called man. It will be seen that the code selector D may have access to as many codes as desired in the same manner as the switch C (Fig. 1) and that the switch 100 D is released immediately after signalling the called man and is then accessible for use by another subscriber. It will be seen therefore, that I have provided a very efficient and simple method of extending calls from 105 one multiparty line to another and also for signalling another party on the same multiparty line, all by means of codes and that my system is very adaptable especially to 110 rural community systems where it is often desirable to have as many as 12 or 15 stations on a single party line.

Having fully described and ascertained the features and aspects of my invention, what I consider to be new and desire to have 115 protected by Letters Patent will be pointed out in the appended claims.

What I claim as my invention is:

1. In a telephone system, lines, a plurality of stations on each line, an automatic switch 120 for extending connection to any of said lines, a signal for each station on a line, means for operating the signals on a line, consisting of an auxiliary code selecting switch associated with said automatic switch, and a code 125 interrupter having a series of contacts and a wiper co-operating therewith, the contacts of said code interrupter connected in pairs to various contacts accessible to said code selector, and means for operating the code 130

- selector to pick out a certain set of contacts on the code interrupter to cause the signals of the stations on the called line to be operated in accordance with a code of a certain subscriber. 6
2. In a telephone system, lines, a plurality of stations on each line, automatic progressively movable switches for establishing a connection between a pair of said lines, a signal for each station on the called line, a rotary switch having a wiper adapted to move over a series of contacts to connect ground thereto, and a code selector associated with one of said progressively movable switches having means for connecting a ringing relay to various contacts of said rotary switch, a ringing relay operated by the connection of ground to the various contacts to which it is connected to operate the signals of the stations on the called line in accordance with a predetermined code. 10
3. In a telephone system, a line, a plurality of stations on said line, a ring back switch accessible to said line having wipers, a code interrupter switch accessible to said ring back switch, said code interrupter consisting of a series of contacts and a wiper for connecting one side of a battery successively to said contacts, a code selector operated in response to a digit of the called number to establish connections from its wiper to any of the contacts of said code interrupter, and a ringing relay for the ring back switch operated in accordance with the code of the called line to ring the bells of the stations on the called line, as the wiper of the code interrupter connects with the selected contacts. 25
4. In a telephone system, a line, a plurality of stations on said line, a ring back switch accessible to said line having wipers, a code interrupter switch accessible to said ring back switch, said code interrupter consisting of a series of contacts and a wiper for connecting one side of a battery successively to said contacts, a code selector operated in response to a digit of the called number to establish connections from its wipers to any of the contacts of said code interrupter, a ringing relay for the ring back switch operated in accordance with the code of the called line to ring the bells of the stations on the called line, as the wiper of the code interrupter connects with the selected contacts, and means controlled by the response of the called subscriber for releasing said code selector switch. 40
5. In a telephone system, a ring back switch having a ringing relay for connecting a generator to a party line to ring the bells of the stations thereon, a progressively movable rotary switch having a wiper and a series of contacts successively connected with thereby, wipers and a bank of contacts for the ring back switch, said wiper controlled by a calling subscriber to establish connection with a plurality of the contacts in the bank of said rotary switch, and means in the ring back switch controlled by the successive connection of the wiper of the rotary switch with its contacts for intermittently closing the circuit of said ringing relay to operate the bells of the stations on a called line in accordance with the predetermined code of a certain station thereon. 70
6. In a telephone system, a ring back switch having a ringing relay for connecting a generator to a party line to ring the bells of the stations thereon, a progressively movable rotary switch having a wiper and a series of contacts successively connected with thereby, wipers and a bank of contacts for the ring back switch, said last mentioned wipers controlled by a calling subscriber to establish connection with a plurality of the contacts in the bank of said rotary switch, and means in the ring back switch controlled by the successive connection of the wiper of the rotary switch with its contacts, for intermittently closing the circuit of said ringing relay to operate the bells of the stations on a called line in accordance with the predetermined code of a certain station thereon, and means controlled by the response of the subscriber at the called station for releasing said ring back switch. 80
7. In a telephone system, party lines, connector switches and ring back switches accessible to one of said lines for signaling a party on another party line and a party on the same line, respectively, a code selector for the connector, a code selector for the ring back switch, and code interrupters accessible to said code selectors, each of said code selectors having means responsive to a plurality of digits of a called number for picking out a particular set of contacts in the bank of the code interrupter, said code interrupter consisting of a rotatable wiper operated from the code selector to successively ground the contacts in its bank to signal the called subscriber. 90
8. In a telephone system, a line, a plurality of stations on said line, an automatic switch accessible thereto having a ringing relay for connecting a generator to said line to operate the signals at said stations, an interrupter, an auxiliary rotary switch for said automatic switch for controlling said ringing relay, said rotary switch adapted to connect said interrupter in series with said ringer relay and battery at one stage of the movement of the switch to allow said relay to be intermittently energized to connect said generator to the line, and adapted at another stage in its movement to temporarily disconnect the interrupter from the relay, and at another stage to permanently disconnect the interrupter from the relay. 100
9. In a telephone system, a line, a plurality of stations on said line, an automatic switch accessible thereto having a ringing relay for connecting a generator to said line to operate the signals at said stations, an interrupter, an auxiliary rotary switch for said automatic switch for controlling said ringing relay, said rotary switch adapted to connect said interrupter in series with said ringer relay and battery at one stage of the movement of the switch to allow said relay to be intermittently energized to connect said generator to the line, and adapted at another stage in its movement to temporarily disconnect the interrupter from the relay, and at another stage to permanently disconnect the interrupter from the relay. 110
10. In a telephone system, a line, a plurality of stations on said line, an automatic switch accessible thereto having a ringing relay for connecting a generator to said line to operate the signals at said stations, an interrupter, an auxiliary rotary switch for said automatic switch for controlling said ringing relay, said rotary switch adapted to connect said interrupter in series with said ringer relay and battery at one stage of the movement of the switch to allow said relay to be intermittently energized to connect said generator to the line, and adapted at another stage in its movement to temporarily disconnect the interrupter from the relay, and at another stage to permanently disconnect the interrupter from the relay. 120
11. In a telephone system, a line, a plurality of stations on said line, an automatic switch accessible thereto having a ringing relay for connecting a generator to said line to operate the signals at said stations, an interrupter, an auxiliary rotary switch for said automatic switch for controlling said ringing relay, said rotary switch adapted to connect said interrupter in series with said ringer relay and battery at one stage of the movement of the switch to allow said relay to be intermittently energized to connect said generator to the line, and adapted at another stage in its movement to temporarily disconnect the interrupter from the relay, and at another stage to permanently disconnect the interrupter from the relay. 130

whereby the bells of said stations may be operated in accordance with a predetermined code.

9. In a telephone system, a line, a plurality of stations on said line, means controlled from one of the stations on said line for operating the call signals at all the other stations on said line in accordance with a predetermined code, consisting of a pair of control relays, a progressively movable interrupter switch, a pair of wipers operable to connect said control relays to different sets of the contacts of said interrupter to variably control a circuit, and a ringing relay in the circuit controlled by said relays to first ring the bells a number of times and then a further number of times after a pause, the code depending upon which contacts of the interrupter the control relays are connected to.

10. In a signaling system, a line, a signal on said line, a source of signaling current, a relay for controlling the application of said source to said line to operate said signal, a circuit for said ringing relay, and a pair of control relays for controlling the circuit of said ringing relay to cause the latter to apply signaling current to the line to operate said signal in accordance with a particular code.

11. In a signaling system, a line, a signal on said line, a source of signaling current, a relay for controlling the application of said source to said line to operate said signal, a circuit for said ringing relay, a pair of control relays for controlling the circuit of said ringing relay to cause the latter to apply signaling current to the line to operate said signal in accordance with a particular code, circuits for said control relays, and a progressively movable switch having a set of contacts and a wiper movable thereover for controlling the action of the control relays.

12. In a signaling system, a line, a signal on said line, a source of signaling current, a ringing relay for controlling the application of said source to said line to operate said signal, a circuit for said ringing relay, a pair of control relays for controlling the circuit of said ringing relay to cause the latter to apply signaling current to the line to operate said signal in accordance with a particular code, circuits for said control relays, a progressively movable switch having a set of contacts and a wiper movable thereover for controlling the action of the control relays, and an interrupter in the ringing relay circuit for controlling the action of the ringing relay.

13. In a signaling system, a line, a signal on said line, a source of signaling current, a ringing relay for controlling the application of said source to said line to operate said signal, a circuit for said ringing relay, a

pair of control relays for controlling the circuit of said ringing relay to cause the latter to apply signaling current to the line to operate said signal in accordance with a particular code, and an interrupter in the ringing relay circuit for controlling the action of the ringing relay.

14. In a signaling system, a line, a signal on said line, a source of signaling current, a ringing relay for controlling the application of said source to said line to operate said signal, a circuit for said ringing relay, a pair of control relays for controlling the circuit of said ringing relay to cause the latter to apply signaling current to the line to operate said signal in accordance with a particular code, circuits for said control relays, a progressively movable switch having a set of contacts and a wiper movable thereover for controlling the action of the control relays, an interrupter in the ringing relay circuit for controlling the action of the ringing relay, and an interrupter for controlling the step by step action of said rotary switch.

15. In a signaling system, a line, a signal on said line, a source of signaling current, a ringing relay for controlling the application of said source to said line to operate said signal, a circuit for said ringing relay, a pair of control relays for controlling the circuit of said ringing relay to cause the latter to apply signaling current to the line to operate said signal in accordance with a particular code, circuits for said control relays, a progressively movable switch having a set of contacts and a wiper movable thereover for controlling the action of the control relays, and an interrupter in the ringing relay circuit for controlling the action of the ringing relay, one of said control relays completing the circuit of the ringing relay to render the ringing relay subject to the interrupter.

16. In a signaling system, a line, a signal on said line, a source of signaling current, a ringing relay for controlling the application of said source to said line to operate said signal, a circuit for said ringing relay, a pair of control relays for controlling the circuit of said ringing relay to cause the latter to apply signaling current to the line to operate said signal in accordance with a particular code, and an interrupter in the ringing relay circuit for controlling the action of the ringing relay, one of said control relays completing the circuit of the ringing relay to render the ringing relay subject to the interrupter.

17. In a signaling system, a line, a signal on said line, a source of signaling current, a ringing relay for controlling the application of said source to said line to operate said signal, a circuit for said ringing relay, a pair of control relays for controlling the

- 6 circuit of said ringing relay to cause the latter to apply signaling current to the line to operate said signal in accordance with a particular code, circuits for said control relays, a progressively movable switch having a set of contacts and a wiper movable thereover for controlling the action of the control relays, an interrupter in the ringing relay circuit for controlling the action of the ringing relay, and an interrupter for controlling the step by step action of said rotary switch, one of said control relays completing the circuit of the ringing relay to render the ringing relay subject to the interrupter. 10
- 16 18. In a signaling system, a line, a signal on said line, a source of signaling current, a ringing relay for controlling the application of said source to said line to operate said signal, a circuit for said ringing relay, 20 a pair of control relays for controlling the circuit of said ringing relay to cause the latter to apply signaling current to the line to operate said signal in accordance with a particular code, circuits for said control relays, a progressively movable switch having a set of contacts and a wiper movable thereover for controlling the action of the control relays, and an interrupter in the ringing relay circuit for controlling the action of the ringing relay, one of said control relays completing the circuit of the ringing relay to render the ringing relay subject to the interrupter, the other of said control relays operating to render the ringing relay non- 30 responsive to the interrupter. 25
- 30 19. In a signaling system, a line, a signal on said line, a source of signaling current, a ringing relay for controlling the application of said source to said line to operate said signal, a circuit for said ringing relay, a pair of control relays for controlling the circuit of said ringing relay to cause the latter to apply signaling current to the line to operate said signal in accordance with a 40 particular code, and an interrupter in the ringing relay circuit for controlling the action of the ringing relay, one of said control relays completing the circuit of the ringing relay to render the ringing relay subject to the interrupter, the other of said control relays operating to render the ringing relay non- 45 responsive to the interrupter. 50
- 55 20. In a signaling system, a line, a signal on said line, a source of signaling current, a ringing relay for controlling the application of said source to said line to operate said signal, a circuit for said ringing relay, a pair of control relays for controlling the circuit of said ringing relay to cause the latter to apply signaling current to the line to operate said signal in accordance with a particular code, circuits for said control relays, a progressively movable switch having a set of contacts and a wiper movable thereover for controlling the action of the con- 60 trol relays, an interrupter in the ringing relay circuit for controlling the action of the ringing relay, and an interrupter for controlling the step by step action of said rotary switch, one of said control relays completing the circuit of the ringing relay to render the ringing relay subject to the interrupter, the other of said control relays operating to render the ringing relay non- 70 responsive to the interrupter. 75
18. In a signaling system, a line, a signal on said line, a source of signaling current, a ringing relay for controlling the application of said source to said line to operate said signal, a circuit for said ringing relay, a pair of control relays for controlling the circuit of said ringing relay to cause the latter to apply signaling current to the line to operate said signal in accordance with a particular code, circuits for said control relays, a progressively movable switch having a set of contacts and a wiper movable thereover for controlling the action of the control relays, and an automatic progressively movable switch having wipers for variably connecting said control relays to the contacts of the rotary switch. 80
22. In a telephone system, an automatic switch, a ringing relay for the switch, a pair of control relays for controlling the circuit of the ringing relay to apply generator to the called line to signal the subscribers thereon, a rotary interrupter switch having a wiper and a series of contacts successively grounded thereby, means for connecting said control relays to a predetermined set of contacts in said rotary switch, one of said relays energized and locked energized by the first movement of the switch to start the intermittent operation of the ringing relay, the other relay energized when the wiper of the rotary switch meets the contact to which it is connected, to temporarily render the ringing relay inoperative, and said first relay unlocked when the wiper meets another contact to which this relay is connected to stop the operation of the ringing relay, whereby the call signals of the called line may be operated in accordance with a code. 95
23. In a telephone system, a line, an automatic connector switch for connecting with said line, a ringing relay for applying ringing current to said line, a code selector, a code interrupter, bank contacts in said code interrupter connected to bank contacts in said code selector, means for operating said code selector to pick a particular set of contacts in said code interrupter, and means for applying ground to the selected bank contacts in said code interrupter to 100 variably operate said ringing relay in applying ringing current to said line. 115
24. In a telephone system, a party line having a plurality of substations thereon, a code interrupter, an operating magnet 120
- 125
- 130

therefor, a ringing relay for applying ringing current to said line, means for operating said ringing relay and said operating magnet in synchronism, and means controlled by 5 said code interrupter for intermittently stopping the operation of said ringing relay to apply a code ring to said ringing relay.

25. In a telephone system, a party line having a plurality of substations thereon, 10 an automatic switch adapted to connect with said line, a code selecting switch associated with said automatic switch, a code interrupter having bank contacts accessible to said code selector, a relay in said automatic 15 switch, and means for intermittently applying ground to the bank contacts of said code interrupter to variably operate said relay in applying ringing current to side line.

26. In a telephone system, lines, a plurality of substations on each line, an automatic switch, another automatic switch associated therewith, means whereby a subscriber on one of said lines may establish a connection with another of said lines by 25 means of said first automatic switch, a code interrupter having contacts connected in pairs accessible to said other automatic switch, a ringing relay in said first automatic switch, and means for applying 30 ground to a pair of bank contacts in said code interrupter to variably energize said ringing relay to selectively signal the parties on the connected line.

27. In a telephone system, an automatic 35 switch, a ringing relay therefor, a ringing interrupter having bank contacts accessible thereto, means for operating said relay and said interrupter in synchronism, means for picking out a certain set of said bank contacts in said interrupter, and means for preventing the operation of said relay while the interrupter engages said certain contacts to cause said relay to ring a predetermined code.

45. 28. In a party line telephone system, a final connector controllable in accordance with digits in a called number for completing connection to a party line, an auxiliary code selector responsive to other digits in the number, and automatic code generating means for signalling the called line according to a definite code, the said code comprising a plurality of groups of signals, and the number of groups and the number of signals in 50 a group corresponding to the number and denomination of the digits in accordance with which the said code selector is operated.

29. In a code ringing mechanism, a two movement code selector switch, means for 60 transmitting two successive series of impulses to said switch to operate it, and code generating mechanism automatically responsive thereafter to produce a code made up of two groups of signals, the number of signals in said groups corresponding, re-

spectively, to the number of impulses in said series.

30. In a code ringing machine, a code selector switch having step by step primary and step by step secondary movements, means 70 for operating said switch to select a code, and code generating mechanism for producing automatically two groups of signals corresponding, respectively, to the number of steps taken by the said code selector in 75 its two movements.

31. In a party line telephone system, an automatic connector switch for completing connections to called lines, and code ringing mechanism associated with said connector comprising two step by step switches having 80 their banks permanently wired together.

32. In a party line telephone system, an automatic connector switch for completing connections to called lines, a code selector 85 associated with said connector for selecting code signals corresponding to desired stations on connected called lines, and a code interrupter switch having its bank permanently wired to the bank of said selector 90 switch.

33. In a party line telephone system, an automatic connector switch for completing connections to called lines, a ringing relay individual to said connector, and two automatic step by step switches co-operating for controlling said relay in accordance with predetermined codes, one of said switches being subscriber controlled in order to select 95 the particular codes desired.

34. In a code ringing machine, a code selector switch having a pair of wipers and associated banks of contacts, code stop and spacing relays connected to said wipers, respectively, a code interrupter switch having an automatically driven wiper and associated bank, and connections from the bank of said interrupter switch to both banks of said code selector switch for controlling said relays.

35. In a code ringing machine, a subscriber controlled code selector switch, an automatically operated interrupter switch, permanent connections between the banks of said switches, and ringing mechanism in 115 said selector switch controlled by said interrupter switch over the said bank connections.

36. In a code ringing machine, a subscriber controlled code selector switch, an 120 automatically operated interrupter switch, permanent connections between the banks of said switches, ringing mechanism in said selector switch, and ringing control relays in said selector controlled by said interrupter 125 switch over said bank connections.

37. In a code ringing machine, a subscriber controlled code selector switch, an automatically operated interrupter switch, permanent connections between the banks of 130

- said switches, a ringing relay, a starting relay initially energized by said interrupter switch for closing a circuit for said ringing relay, a spacing relay for breaking the circuit of said ringing relay, and a circuit for said spacing relay including one of said bank connections. 55
38. In a code ringing machine, a subscriber controlled code selector switch, an automatically operated interrupter switch, permanent connections between the banks of said switches, a ringing relay, a starting relay initially energized by said interrupter switch for closing a circuit for said ringing relay, a spacing relay for breaking the circuit of said ringing relay, a circuit for said spacing relay including one of said bank connections, and a circuit established over another one of said bank connections for 60 short circuiting said starting relay to de-energize the same. 70
39. In a code ringing machine, a subscriber controlled code selector switch, an automatically operated interrupter switch, permanent connections between the banks of said switches, a ringing relay, and a circuit therefor, two relays in said selector switch, one for closing said circuit and the other for opening it, and circuits for said selector 75 relays closed by said interrupter switch over said bank connections. 80
40. In a code ringing machine, a ringing relay, a starting relay for closing a control circuit for said ringing relay, means for energizing said starting relay to start the transmission of a code signal, a spacing relay and an interrupter co-operating to control said circuit to produce the code signal, and means for short circuiting said starting 85 relay to deenergize the same at the end of the code signal. 90
41. In a code ringing machine, a subscriber controlled code selecting switch, an automatic code interrupter switch, a ringing relay in said selector switch, a motor magnet for said interrupter switch, and circuits for energizing said relay and magnet simultaneously. 95
42. In a code ringing machine, a directly controlled code selecting switch, an automatic code interrupter switch, a ringing
- relay in said selecting switch and a motor magnet for said interrupter switch, a circuit having two branches, one branch including said relay and the other branch including 65 said magnet, and a device for intermittently closing said circuit. 75
43. In a code ringing machine, a directly controlled code selecting switch, an automatic code interrupter switch, a ringing relay in said selecting switch and a motor magnet for said interrupter switch, a circuit having two branches, one branch including said relay and the other branch including 80 said magnet, a device for intermittently closing said circuit, and relays in the selector switch controlled by the interrupter switch for opening and closing the 85 said relay branch independent of the said motor magnet branch. 90
44. In a code ringing machine, a directly controlled code selecting switch, an automatic code interrupter switch, a ringing relay in said selecting switch and a motor magnet for said interrupter switch, a circuit having two branches, one branch including 75 said relay and the other branch including said magnet, a device for intermittently closing said circuit, a code start and stop relay and a code spacing relay for controlling the said relay branch, and circuits controlled by the wiper of said interrupter switch for energizing and deenergizing said code relays. 80
45. In a party telephone system, a connector switch for connecting with a called party line, an auxiliary code selector switch having bank contacts arranged in levels, means for operating said code selector in accordance with the code desired to advance 90 its wipers to a particular level and to a particular set of contacts in the selected level, a ringing relay, and means for automatically operating said relay a plurality of times corresponding to the number of the 95 selected level and then a plurality of times corresponding to the number of the selected contact set in such level. 95

Signed by me at Chicago, Cook County, Illinois, this 24th day of June, 1919.

MARTIN L. NELSON.
